Primary Examiner — Rhea Shields(74) *Attorney, Agent, or Firm* — Luedeka Neely, P.C.(57) **CLAIM**

The ornamental design for a U-shaped box, as shown and described.

DESCRIPTION

FIG. 1 is a perspective view of a U-shaped box of our new design.

FIG. 2 is a frontal view thereof.

FIG. 3 is a rear view thereof.

FIG. 4 is a top view thereof.

FIG. 5 is a bottom view thereof.

FIG. 6 is a left-side view thereof; and,

FIG. 7 is a right-side view thereof.

The dashed lines show perforations formed on the U-shaped box.
